WITNESS:

INVENTOR
BY *Victor J. Evans*

ATTORNEY

UNITED STATES PATENT OFFICE.

WILLIAM W. SPENCER, OF KENDALLVILLE, INDIANA.

BOOKHOLDER.

Application filed July 10, 1926. Serial No. 121,656.

The object is the provision of a book holder of an extremely simple construction which may be cheaply manufactured and marketed at a reasonable selling price, and which includes a frame on which there is hung a book support having its lower edge formed with an upstanding lip to contact with the exposed pages of an open book, and which has its lower or book supporting part swingable through the frame so that books of varying thicknesses may be successfully held in open position, the frame being leg supported and being arranged at an angle so that the open book is tilted at a convenient angle with respect to the reader.

To the attainment of the foregoing, the invention consists in the improvement as hereinafter described and definitely claimed.

In the drawing the figure illustrates a perspective view of a book holder in accordance with this invention.

As disclosed by the drawings, both the frame and book support may be constructed of wire, although, it is, of course, to be understood that other material may be employed.

The frame comprises an outer substantially U-shaped body whose parallel arms are indicated by the numeral 1 and the connecting element for the arms by the numeral 2. The arms 1 have their lower ends rounded and extended at upward angles, as indicated by the numeral 3, and these angle portions have their ends rounded upon themselves to provide foot portions 4. As a matter-of-fact, the inner rounded connecting portions 5 between the arms 2 and 3 likewise serve as legs, both these portions 5 and the portions 4 resting on a desk or like support.

In the showing of the drawing there is connected to the arms 1, adjacent their rounded ends 5, a transverse wire member 6, and this wire member, at suitable points equi-distant from the center thereof, is rounded upon itself to provide eyes 7. Through these eyes there are passed the parallel arms 8 of a substantially U-shaped wire member 9. The upper ends of the wire

members are bent around the top element 2 of the frame.

Hung on the top member adjacent to the sides 1 of the frame there are the parallel arms 10 of the book support. The arms 10 have their ends rounded to provide eyes 11 that engage with the member 2 of the frame. The lower inner ends of the arms 10 are bent outwardly at right angles, as indicated by the numeral 12, and from thence bent upwardly, as at 13, the said portions 13 being connected by the remaining strand 14 of the wire that constitutes the book holder.

The elements 13 and 14 provide a lip, the lower edges of the book resting directly upon the arms 10. It will be apparent that by swinging the lower portion of the book support through the frame the distance between the lip of the support and the body of the frame may be regulated so that books of varying thicknesses may be accommodated by the holder.

While I have illustrated a satisfactory embodiment of my improved device my features of invention are capable of extended application and I do not wish to be restricted to the precise details herein shown and described.

Having described the invention, I claim:

In a device for the purpose set forth, a wire frame comprising an outer substantially U-shaped part, the parallel arms of which are rounded and extend rearwardly at an upward angle and merge into downwardly rounded portions providing with the first mentioned rounded portion feet, a cross member connecting the sides of the frame, strands extending vertically and connecting the cross member with the top of the frame, a swingable holder hinged from said top having horizontal portions extending through the frame, said horizontal portions being provided with bent-up portions connected by a transverse portion at the front of the frame.

In testimony whereof I affix my signature.

WILLIAM W. SPENCER.
